CUTTER CHAIN

Leon E. Simmons, Claremont, N. H., assignor to
Joy Manufacturing Company, a corporation of
Pennsylvania

Continuation of application Serial No. 515,493,
December 24, 1943. This application March 19,
1948, Serial No. 15,931

3 Claims. (Cl. 262—33)

1

This invention relates to cutter chains and more particularly to an improved cutter bit and cutter bit mounting and holding means for a mining machine cutter chain.

An object of the present invention is to provide an improved cutter chain. Another object is to provide an improved mounting and holding means for a cutter bit. A further object is to provide an improved cutter bit. Yet another object is to provide an improved cutter bit having improved gauging means and holding means associated therewith. A further object is to provide an improved cutter bit of the double pointed, reversible type having shoulders providing abutment surfaces formed on its cutting faces in a novel manner. A still further object is to provide an improved bit holder for a small, double pointed, reversible cutter bit. Other objects and advantages of the invention will, however, hereinafter more fully appear.

The present application is a continuation of my copending application Serial No. 515,493, filed December 24, 1943, now abandoned.

In the accompanying drawing there are shown for purposes of illustration two embodiments which the invention may assume in practice.

In this drawing:

Fig. 1 is a side elevational view of a portion of a cutter chain constructed in accordance with an illustrative embodiment of the invention.

Fig. 2 is a cross sectional view taken substantially on line 2—2 of Fig. 1, looking toward the front of the chain block.

Fig. 3 is a view in longitudinal vertical section taken substantially on line 3—3 of Fig. 2.

Fig. 4 is a horizontal sectional view taken substantially on line 4—4 of Fig. 3.

Fig. 5 is a perspective view of the improved cutter bit shown in Fig. 3.

Fig. 6 is a perspective view of the improved bit holder.

Fig. 7 is a vertical sectional view similar to Fig. 3, showing a modified form of the invention.

Fig. 8 is a perspective view of the front bit clamp shown in Fig. 7.

In both illustrative embodiments of the invention, the improved cutter bit and bit supporting and holding means are shown associated with a mining machine cutter chain comprising a series of chain blocks 1 pivotally connected at 2 to strap links 3. The chain blocks and strap links have lateral gibs 4 and 5 respectively, receivable in the guideways of a conventional cutter bar of a coal mining machine. It will be evident that the invention may be associated with chain blocks and strap links of various other designs, if desired.

In the embodiment of the invention shown in Figs. 1 to 6 inclusive, the chain block has a socket 6 disposed at substantially right angles to

2

the path of travel of the chain, and an upstanding lug 7 is formed integral with the block in advance of the socket and has an inwardly and rearwardly sloping surface 8 extending along the forward wall of the socket in the manner shown in Fig. 3. There is a detachable holder 9 having a head 10 and a shank 11, the latter being received in the block socket 6 in engagement with the rear socket wall. The holder has a recess 12 opening forwardly through its forward side and shaped to receive a cutter bit 13 of a novel design. This cutter bit is preferably of generally rhomboidal shape in side elevation and has stepped front and rear cutting faces 14 and 15 whose portions are parallel to a common plane and make up elongated diamond shapes terminating in cutting points 16 at the opposite extremities of the bit on the opposite sides of the bit body. The bit is preferably generally diamond shape in cross section and is preferably cut from a piece of bar stock of the desired material and shape, as disclosed in my Patent No. 2,418,320. The cutting faces of the bit are stepped in a novel manner, resulting in overhanging shoulders 17 providing abutment surfaces 18 disposed at right angles to the cutting faces. The inner part of the front face of the cutter bit, when the latter is in cutting position on the chain block, rests against the inclined surface 19, with the front abutment surface 18 of the bit engaging the outer surface of the upstanding lug 7, as shown in Fig. 3, and the inner portion extends inwardly into the chain block socket and into the holder recess 12. The rear surface of the cutter bit engages the inclined bottom wall 19 of the holder recess 12, with a shoulder 20 on the holder overlying the abutment surface 18 on the rear bit face. At the forward side of the chain block, a set screw 21 is threaded in an inwardly and downwardly inclined opening 22 in the chain block beneath the upstanding lug 7, and the inner end of the set screw engages an inclined surface 23 on the forward side of the lower portion of the holder shank 11. The sides 24 of the holder at the opposite sides of the recess 12 engage the opposite sides of the cutter bit in the manner shown in Fig. 4. The holder shank is traversed by an opening 25 which enters the lower portion of the bit receiving recess 12, and the inner inactive cutting point 16 of the cutter bit is received in this opening. When the set screw 21 is tightened, the holder 9 is thrust rectilinearly inwardly within the block socket to clamp firmly the cutter bit against the inclined surface 8 on the chain block. The abutment surface 18 on the front face of the cutter bit predetermines the bit gauge, while the abutment surface 18 on the rear bit face cooperates with the shoulder 20 on the holder to lock the cutter bit against longitudinal displacement from the

holder recess. When the set screw is loosened, the holder may be moved outwardly in the block socket a slight distance to disengage the shoulder 20 from the rear abutment surface 18 on the bit to enable the cutter bit to be readily released from the holder recess 12, and the bit may be reversed end for end and reinserted in the holder recess and again clamped in cutting position on the block simply by tightening the set screw. Accordingly, when one cutting point of the bit becomes dull, a sharp point may be presented to the work, and the bit, due to its relatively inexpensive design, may be discarded when both points become dull.

The modified embodiment shown in Figs. 7 and 8 is similar to that shown in Fig. 3 with the exception that the front face of the bit does not rest directly against the chain block, and the shoulder at the front face of the bit does not lie against the outer surface of an upstanding front lug. In this construction, the front upstanding lug is omitted and an inclined rearwardly facing surface 26 extends inwardly and rearwardly along the front wall of the chain block socket. Engaging this inclined surface is a front holder member or bit clamp 27 having a socket 28 for receiving the inner portion of the cutter bit 29, the latter being similar to the cutter bit shown in Fig. 5. The front holder member has a rearwardly facing inclined surface 30 extending into the socket 28, and the front face of the cutter bit rests against this surface with the shoulder at the front face of the bit resting against the outer end of the front holder member. A rear holder 31, similar to the holder 9 shown in Fig. 6, has its shank received in the block socket and engaging the rear socket wall. This holder has a recess 32 opening forwardly through its front face for receiving the cutter bit in the manner shown in Fig. 7. When the set screw 33, similar to the set screw 21, is tightened, the rear holder 31, together with the front holder member 27, are thrust inwardly in the block socket to effect clamping of the bit with a wedgelike action in cutting position on the chain block. As in the form of the invention shown in Fig. 3, the rear holder has a shoulder which cooperates with the abutment surface 18 on the rear face of the cutter bit for locking the bit within the holder recess.

As a result of this invention, an improved cutter chain is provided having improved bit mounting and holding means, whereby a cutter bit may be secured in cutting position on a chain block in an improved manner. It will further be evident that an improved cutter bit is provided which has novel means for predetermining the bit gauge and for interlocking the bit with its holder means. Other uses and advantages of the invention will be clearly apparent to those skilled in the art.

While there are in this application specifically described two embodiments which the invention may assume in practice, it will be understood that these embodiments are disclosed for purposes of illustration and that the invention may be modified and embodied in various other forms without departing from its spirit or the scope of the appended claims.

What I claim as new and desire to secure as Letters Patent is:

1. In a cutter chain, a chain block having a socket and a rearwardly facing inclined surface at the forward wall of the socket, a reversible cutter bit having spaced cutting faces termi-

nating in cutting points at the opposite extremities of the bit and having shoulders on its cutting faces providing abutment surfaces, the front face of the bit engaging said inclined rearwardly facing block surface with the abutment surface of its front shoulder resting against the outer surface of the block, and a holder received in said block socket and having a recess for receiving the inner portion of the cutter bit, the inner wall of the recess having a shoulder cooperating with the abutment surface of the shoulder of the rear bit face for locking the bit in said holder recess.

2. In a cutter chain, a chain block having a socket and a front upstanding abutment providing a rearwardly facing inclined surface at the forward wall of said socket with said surface extending forwardly and outwardly from said socket, a reversible cutter bit having spaced cutting faces terminating in cutting points at the opposite extremities of the bit and having shoulders on its cutting faces providing abutment surfaces, the front face of said bit engaging said inclined rearwardly facing surface with the abutment surface of its front shoulder resting against the outer surface of said front upstanding abutment exteriorly of said block, and a holder received in said block socket and having a recess for receiving the inner portion of said cutter bit, the inner wall of said recess having a shoulder cooperating with the abutment surface of the shoulder of the rear bit face for locking said bit in said holder recess, said holder as it is thrust inwardly in said socket firmly securing said front bit shoulder against said outer surface of said upstanding abutment.

3. In a cutter chain, a chain block having a socket and a rearwardly facing inclined surface at the forward wall of the socket, a reversible cutter bit having a body providing spaced cutting faces terminating in cutting points at the opposite extremities of the bit and having shoulders on its opposite faces providing abutment surfaces projecting from said spaced bit faces, the front face of said bit engaging said inclined rearwardly facing surface with the abutment surface of its front shoulder resting against the outer surface of said block, and a holder received in said block socket and having an outwardly and forwardly inclined forwardly facing surface with which the rear bit face engages, said holder surface having a shoulder cooperating with the abutment surface of the shoulder on the rear bit face for locking said bit to said holder, said holder as it is thrust inwardly in said socket acting on said rear abutment surface to hold said front abutment surface tightly against the outer surface of said block with the bit body between said abutment surfaces placed under longitudinal tension.

LEON E. SIMMONS.
